HERBERT A. WALLACE, OF EDGEWOOD BOROUGH, PENNSYLVANIA, ASSIGNOR TO THE UNION SWITCH AND SIGNAL COMPANY, OF SWISSVALE, PENNSYLVANIA, A CORPORATION OF PENNSYLVANIA

RAILWAY-TRAFFIC-CONTROLLING APPARATUS.

Application filed September 24, 1925. Serial No. 58,308.

My invention relates to railway traffic controlling apparatus, and particularly to apparatus of the type comprising train carried governing means responsive to traffic conditions. More particularly, my invention relates to governing means for causing an automatic application of the brakes upon a change from less restrictive to more restrictive traffic conditions in advance of the train.

One object of my present invention is the provision, in apparatus of the type described above, of a novel arrangement of apparatus for releasing the brakes after such automatic application.

I will describe two forms of railway traffic controlling apparatus embodying my invention, and will then point out the novel features thereof in claims.

In the accompanying drawings, Fig. 1 is a view, partly diagrammatic, illustrating one form of railway traffic controlling apparatus embodying my invention. Fig. 2 is a view illustrating a modified form of the apparatus shown in Fig. 1 and also embodying my invention.

Similar reference characters refer to similar parts in both views.

Referring first to Fig. 1, the reference character L designates a brake application valve comprising a pressure chamber 2 and a valve chamber 3, separated by a reciprocable piston 4. The valve chamber 3 is constantly supplied with fluid pressure, usually air, from a source not shown in the drawing, through pipe 1. The piston 4 is provided with a restricted orifice 4^a through which the pressure supplied to chamber 3 may gradually flow into chamber 2. Chamber 2 is connected with a pipe 2^a which leads to two branch pipes 17 and 41. When these two pipes are blanked, pressure admitted to chamber 2 through orifice 4^a, combines with the force exerted by a spring 5 to move piston 4 to the right against the pressure in chamber 3. When chamber 2 is connected with atmosphere, however, the piston 4 is moved to the left by pressure in chamber 3. The piston 4 operates a slide valve 6 controlling a plurality of valve ports.

The reference character 50 designates a pipe which is normally supplied with fluid pressure and which is arranged to apply the brakes when pressure in this pipe is reduced.

When the piston 4 is in its normal or right-hand position, pipe 50 is blanked by valve 6. When piston 4 is in its reverse or left-hand position, pipe 50 is connected with atmosphere through ports 26 and 40, to cause an automatic brake application.

The reference character H designates a relay valve comprising a valve stem 7 provided with an armature 10 and a winding 11. The winding 11 is controlled by traffic conditions in advance of the train so that under safe traffic conditions the winding 11 is energized from a source not shown in the drawing. Under dangerous traffic conditions the winding 11 is de-energized. When winding 11 is energized, valve stem 7 is moved downwardly and fluid pressure then flows from a source not shown in the drawing through pipe 9, valve H, and pipe 12 to chamber 14 of repeater valve J. Pressure thus supplied to pipe 12 also charges the timing reservoir 13. The repeater valve J comprises a valve stem 15 controlled by a diaphragm 14^a subjected to the pressure in chamber 14. When chamber 14 is supplied with fluid pressure as just described stem 15 is forced downwardly to blank pipe 17 and to connect pipe 18 with atmosphere through port 16. When winding 11 of valve H becomes de-energized valve stem 7 rises, disconnecting pipe 9 from pipe 12 and connecting pipe 12 with atmosphere through port 8. Pressure in timing reservoir 13 and in chamber 14 of valve J is therefore gradually dissipated to atmosphere. After a time interval the stem 15 of valve J rises, thereby connecting pipe 17 with pipe 18.

Pipe 18 is normally connected through a suppressing valve M, pipe 24, a manually operable release valve A, and pipe 37, with a stop reservoir 38.

The suppressing valve M comprises a chamber 21 containing a piston 21^a. This piston carries a plunger 23 and a valve 20. Pressure in chamber 21 is controlled by an acknowledging valve K and an acknowledging reservoir 31 associated therewith. When the acknowledging valve K is in its normal position, reservoir 31 is supplied with fluid pressure from a source not shown in the drawing through pipe 30. When the valve K is reversed and valve L is in its normal position, the pressure in reservoir 31 is sup-

plied, through valve K, pipe 33, port 27 of valve L and pipe 25 to chamber 21 of suppressing valve M. Piston 21^a is therefore moved upwardly, blanking pipe 18 and sup- 5 plying fluid pressure from a source not shown in the drawing through pipe 19 and valve 20 to pipe 24 and therefore to stop reservoir 38.

The release valve A is a manually operable 10 valve which may be located in such position that the valve is accessible to the engineman only when the train is at rest. As has already been stated, when the valve is in its 15 normal position pipe 24 is connected with pipe 37. When valve A is reversed, however, pipe 37 is blanked and pipe 24 is connected with pipe 42 through pipe 44 and a check valve 45.

When valve L is in the reverse position, 20 pipe 41 is connected, through port 29 with pipe 42. Pipe 42 is connected with a pilot valve G, which is operated by the engineman's brake valve and is closed only when the engineman's brake valve is in the lap 25 position. It will be manifest therefore that if valve G is open when the application valve L reverses, chamber 2 will be connected directly with atmosphere through the path just traced through valve G.

As shown in the drawing, relay valve H 30 is energized. Chamber 14 of valve J and timing reservoir 13 are therefore charged with fluid pressure so that valve J is operated to blank pipe 17. Valve K is in its 35 normal position so that reservoir 31 is charged with fluid pressure. Suppressing valve M is also in its normal position so that valve 20 is closed and pipe 24 is connected with pipe 18. The brake application valve 40 L is in its normal position so that pipe 41 is blanked by valve 6 and pipe 50 is also blanked so that the brakes are released. Valve A is in its normal position thereby connecting pipes 24 and 37 together. Reservoir 38 is therefore connected with atmosphere. Valve G, controlled by the engineman's brake valve is open.

I will now assume that relay valve H becomes de-energized as by a change from 50 less to more restrictive traffic conditions in advance. Chamber 14 of valve J and timing reservoir 13 are therefore connected with atmosphere. After a time interval stem 15 of valve J rises, connecting pipe 17 with stop 55 reservoir 38 through valves M and A. The consequent reduction in the pressure in chamber 2 of valve L causes that valve to reverse, connecting pipe 50 with atmosphere and causing an automatic application of the 60 brakes.

The reversal of valve L connects pipe 41 with atmosphere through port 29, pipe 42, and valve G. The reversal of valve L also connects pipe 37 with atmosphere 65 through ports 28 and 39. Chamber 2 is

therefore connected with atmosphere through two paths; one through pipe 17, valve J, pipe 18, valve M, pipe 24, valve A, pipe 37, port 28 of valve L, and port 39; and the other through pipe 41, port 29 of valve L, pipe 42 and valve G.

In order to release the brakes the engineman first moves his brake valve to the lap position, thereby closing valve G. Pipe 42 is therefore blanked at valve G. The engineman then reverses valve K. This operation of valve K discharges, into pipe 33, the pressure to which the acknowledging reservoir 31 had previously been charged. Valve L is in the reverse position however, 70 and pipe 33 is therefore blanked by slide valve 6. The engineman then operates valve A, thereby disconnecting reservoir 38 from pipe 24 and connecting pipe 24 with pipe 42 through pipe 44, and check valve 45. It 80 will be seen that this operation of valve A blanks all avenues of escape for pressure from chamber 2. Pressure admitted to chamber 2 through the restricted orifice 4^a therefore gradually builds up to the value 90 necessary to restore piston 4 to its normal position. When this operation of valve L takes place, pipe 41 is blanked, pipe 37 is blanked, and pipe 50 is blanked. The blanking of pipe 50 makes it possible for the engineman to release his brakes. The movement of valve L to its normal position also connects pipe 33 with pipe 25. The pressure supplied to pipe 33 from the acknowledging 95 reservoir 31 therefore flows into chamber 21 100 of the suppressing valve M, lifting piston 21^a and plunger 23, and opening valve 20. Pipe 18 is therefore blanked and fluid pressure is supplied to pipe 24 through valve 20. This pressure is supplied through valve A, 105 pipe 44, and check valve 45, to pipe 42, but pipe 42 is blanked at slide valve 6 so that the pressure thus supplied to pipe 24 has no function until the engineman restores valve A to its normal position. When he 110 does so, pressure in pipe 24 flows through valve A to pipe 37. This pipe is blanked at slide valve 6 and the pressure thus supplied thereto charges stop reservoir 38 with fluid pressure. After a time interval the 115 pressure supplied to chamber 21 of valve M is dissipated to atmosphere through a restrictive orifice 22. The piston 21^a therefore returns to its lower position, connecting pipe 18 with pipe 24, but this operation has no 120 effect on the valve L because the stop reservoir is now charged with fluid pressure and therefore the pressure in chamber 2 is not reduced. The engineman can therefore restore the acknowledging valve K to its 125 normal position and can operate his engineman's brake valve to the release or running positions because the consequential opening of valve G can have no effect on the brake application valve since with valve A in the 130

normal position valve G is disconnected from pipe 41.

It should be pointed out that if, after a brake application has been incurred, the valve H again becomes energized, so as to blank pipe 17 at valve J, the engineman can release the brakes, without operating the release valve A, by simply moving his engineman's brake valve to the lap position to close valve G. This will blank pipe 42, and pipe 17 being blanked at valve J, the pressure will build up in chamber 2 to restore the valve L to its normal position.

It should also be pointed out that an automatic application of the brakes can be prevented if the engineman takes proper action upon a change from less to more restrictive traffic conditions. I will assume for example that the apparatus is in the position illustrated in the drawing, and that valve H becomes de-energized. After a time interval valve J opens to connect pipe 17 with pipe 18. If, prior to the operation of valve J, the engineman operates valve K, the pressure in reservoir 31 flows into chamber 21 of suppressing valve M. The resulting operation of valve M blanks pipe 18 and charges stop reservoir 38 with fluid pressure. The blanking of pipe 18 prevents a reduction in the pressure in chamber 2 and therefore the valve L does not operate when valve J opens. When the pressure supplied to chamber 21 becomes dissipated to atmosphere through orifice 22 the suppressing valve M is restored to the condition in which it is illustrated in the drawing thereby connecting pipe 18 with pipe 24. But while valve 20 was open stop reservoir 38 was charged with fluid pressure and therefore when pipe 18 becomes connected with pipe 24 the pressure in chamber 2 is not reduced and the application valve L therefore remains in its normal position. It will be plain from the foregoing that if the engineman takes suitable action by operating the acknowledging valve K a brake application can be prevented even though valve H becomes de-energized.

I will now assume that an automatic application of the brakes has been incurred by de-energization of valve H without the acknowledgement by the engineman to prevent operation of the brake application valve L. I will also assume that the engineman has brought the train to a stop and has proceeded as explained hereinbefore to release the brakes by operation of valves G, A and K. I will further assume that valve A is left in the reverse position so that pipes 44 and 24 are connected together and pipe 37 is blanked. If, under these conditions, the engineman should return to his cab and attempt to proceed with his train by moving his engineman's brake valve away from the lap position, valve G will immediately open. When valve M returns to its normal position

fluid pressure from chamber 2 will immediately escape through pipe 17, valve J, pipe 18, valve M, pipe 24, release valve A, pipe 44, check valve 45, pipe 42, and valve G to atmosphere, and the brake application valve L therefore will reverse to apply the brakes. It will therefore be seen that the apparatus is so arranged as to require the engineman to restore valve A to its normal position before he can proceed after an automatic application of the brakes.

I will now assume that an automatic application of the brakes has been incurred, that the valve G is closed, and that the engineman has reversed valve A in an attempt to release the brakes but that valve L is still in the reverse position. I will further assume that due to a change to proceed conditions in advance, valve H becomes energized. Stem 15 of valve J is therefore driven downwardly. Were it not for the check valve 45 fluid pressure would then escape from chamber 2 through pipe 41, port 29 in slide valve 6, pipe 42, pipe 44, valve A, pipe 24, valve M, pipe 18, and valve J to atmosphere through port 16. With the check valve 45 interposed between pipes 42 and 44 however, this escape of fluid pressure is prevented and the engineman is therefore permitted to release his brakes by proper operation of release valve A even though valve H becomes energized after an automatic application of the brakes due to de-energization of this valve.

Referring now to Fig. 2, a relay R is controlled by traffic conditions in advance in such manner that under safe traffic conditions the relay is continuously energized. When traffic conditions in advance of the train are dangerous, however, the relay R is de-energized briefly and is then re-energized.

In the form here shown the relay R is controlled by a shoe 72 supported in the frame 70 of the locomotive and arranged to co-operate with trackway ramps, one of which is illustrated at Q, and which are located at intervals along the trackway. These ramps are controlled by traffic conditions so that when traffic conditions in advance of a ramp are safe the ramp is withdrawn so as not to engage shoe 72 as the train passes. If traffic conditions are dangerous, however, the ramp is moved into a position wherein it is engaged by the shoe 72 of a passing train. The shoe 72 is biased to the position shown in the drawing by a spring 71. When the shoe is in the position a contact 75-73-74 is closed. When shoe 72 engages a ramp, the shoe is lifted to open the contact 75-73-74. Relay R is connected with terminals B and C of a suitable source of energy not shown in the drawing in series with the contact 75-73-74. It follows that relay R is normally energized, but is de-energized for a brief interval under dangerous traffic conditions when the train passes a ramp Q.

Associated with the main relay R is a stick relay S which is controlled in part by a manually operable circuit controller D. This circuit controller comprises a cylinder 46 containing a piston 47 biased to an upper position by a spring 48. Rigidly attached to the piston 47 is a movable contact finger 49. A second movable contact finger 51 manually operable by the engineman is attached to finger 49 by means of a spring 62. Under normal conditions the piston 47, under the influence of the spring 48, occupies such position that contact 49 is closed and contact 51 is open. If, however, contact 51 is closed, spring 62 overcomes the force exerted by spring 48 and moves piston 47 downwardly to open contact 49. Due to the time required for the escape of air under piston 47, a brief interval of time elapses after the closing of contact 51 and before the opening of contact 49. It will therefore be plain that contact 51 can be closed for a brief interval and re-opened without opening contact 49, but that if contact 51 is permanently closed contact 49 will be held open.

The stick relay S is provided with a pick-up circuit which may be traced from terminal B through wire 57, contact 51 of circuit controller D, wires 58 and 55, winding of relay S, to terminal C. A stick circuit is also provided for this relay from terminal B, through front contact 52 of relay R, wire 53, front contact 54 of stick relay S, wire 55, winding of relay S to terminal C. It will therefore be plain that if the stick relay is once energized by operation of the circuit controller D, the relay will be maintained in its energized condition over its stick circuit as long as relay R remains energized.

The relay valve H' is provided with a winding 11 which is supplied with energy over a circuit which may be traced from terminal B, through contact 49 of circuit controller D, wire 59, front contact 60 of relay S, wire 61, winding 11 of valve H' to terminal C. When winding 11 is energized the valve stem 7 of valve H' is moved downwardly to blank pipe 63. When winding 11 is de-energized, however, the stem 7 is moved upwardly so that pipe 63 is connected with atmosphere through port 8^a. Pipe 63 is one of the branch pipes connected through pipe 2^a with chamber 2 of a brake application valve L' similar to valve L of Fig. 1. The other branch pipe 64 connects with a pipe 65 which is normally blanked by slide valve 6^a of valve L. Pipe 64 also communicates with pipe 66 which is normally blanked by valve A. When valve L reverses, pipe 65 is connected with pipe 42, which pipe is constantly connected with the stop reservoir 38 and with the pilot valve G. When valve A is in its normal position pipe 42 is connected, through pipe 67, valve A, and port 68 to atmosphere. When valve A is re-

versed, however, pipe 67 is connected with pipe 66.

Pipe 50, which controls the brakes, is blanked when the valve L' is in the normal position and is connected with atmosphere 70 when this valve is reversed exactly as already explained in connection with Fig. 1.

As shown in the drawing relay R is energized, circuit controller D occupies its normal position, relay S is energized over its 75 stick circuit, and valve H' is energized, thereby blanking pipe 63. The brake application valve L' is in its normal position and the brakes are released. The release valve A is in its normal position and valve G is 80 open. The stop reservoir 38 is therefore connected with atmosphere. I will now assume that relay R becomes de-energized briefly as by engagement of shoe 53 with a ramp Q. The opening of front contact 52 thereon de- 85 energizes relay S, which latter relay opens. When relay R again becomes energized the closing of contact 52 can not pick up relay S and therefore can not have any effect upon the governing apparatus, unless the change 90 in traffic conditions was acknowledged by proper operation of circuit controller D. Assuming that no such operation of the circuit controller takes place, the opening of front contact 60 of relay S interrupts the 95 circuit for winding 11 of valve H'. Pipe 63 is therefore connected with atmosphere and pressure from chamber 2 flows through pipe 63 and valve H' to atmosphere. Brake application valve L' therefore reverses, connecting pipe 50 to atmosphere and causing an 100 automatic application of the brakes. It should be pointed out that if the engineman attempts to defeat the purpose of relay R by fastening circuit controller D in its operated 105 position, that is, in such position that contact 51 is closed so that the pick-up circuit for stick relay S is complete, contact 49 will be opened, thereby interrupting the circuit 110 for valve H' and causing an automatic application of the brakes.

When valve L' is reversed chamber 2 is connected with atmosphere through pipes 64 and 65, port 29 of slide valve 6, pipe 42 and valve G. Pipe 42 is also connected with atmosphere through valve A. It will therefore be plain that after valve L' is moved to its reverse position it can not be restored to its normal position simply by again energizing valve H'. In order to release the 120 brakes after an automatic application of the brakes the engineman first operates circuit controller D to energize stick relay S. Relay S then remains closed as long as relay R is energized. The closing of contact 60 125 of relay S completes the circuit for valve H'. This valve being closed, pipe 63 is blanked. The engineman next moves his engineman's brake valve to the lap position, thereby closing valve G. The engine- 130

man then reverses valve A, thereby disconnecting pipe 67 from atmosphere and connecting this pipe with pipe 66. All avenues of escape are now closed for fluid pressure 5 from chamber 2. The pressure supplied to this chamber through the restricted port 4^a now gradually builds up. This pressure is, however, supplied to the stop reservoir 38 and in order to charge this reservoir a considerable interval of time is required. When 10 the stop reservoir, the pipe lines connected therewith, and the chamber 2 have been charged to the pressure required to reverse valve L', piston 4 returns to its normal position. The engineman may then restore valve A to its normal position. If the engineman now moves his brake valve to the release or running position, valve G immediately opens but this has no effect upon 15 the rest of the apparatus, because all of the pipes which are connected with chamber 2 of valve L' are now disconnected from valve G.

If, however, the engineman leaves valve 25 A in its reverse position after restoring valve L to its normal position and attempts to move the engineman's brake valve away from the lap position, the opening of valve G immediately vents chamber 2 to atmosphere 30 through pipes 64 and 66, valve A, pipes 67 and 42, and valve G. The apparatus is therefore so arranged that the engineman must return the release valve A to its normal 35 position before he can proceed.

Although I have herein shown and described only two forms of railway traffic controlling apparatus embodying my invention, it is understood that various changes and modifications may be made therein within 40 the scope of the appended claims without departing from the spirit and scope of my invention.

Having thus described my invention, what I claim is:

1. The combination, in railway traffic controlling apparatus comprising a pressure chamber, a valve member arranged to occupy a normal or a reverse position according as the pressure in said chamber is above or below a predetermined value, respectively, and means for constantly supplying fluid pressure to said chamber through a restricted orifice, of a reservoir normally connected with atmosphere, means controlled by traffic conditions for at times disconnecting said reservoir from atmosphere and for connecting the reservoir with said chamber, means for connecting said reservoir and said chamber with atmosphere when said valve member is in its reversed position, a manually operable valve for disconnecting said chamber from atmosphere and from said reservoir, and automatic brake applying mechanism controlled by said valve member.
2. Railway traffic controlling apparatus

comprising a train carried brake application valve having a chamber constantly supplied with fluid pressure through a restricted orifice, a port in said valve normally closed but arranged to be opened when the pressure 70 in said chamber is reduced below a predetermined value, automatic brake application mechanism controlled by said brake application valve, a manually operable release valve located on the train and having a normal and a reverse position, means responsive to traffic conditions and effective when said release valve is in its normal position for reducing the pressure in said chamber below such predetermined value, and means including said port for subsequently connecting said chamber with atmosphere, said last mentioned means being ineffective when said release valve is in its reverse position.

3. Railway traffic controlling apparatus comprising a brake application valve having a chamber constantly supplied with fluid pressure through a restricted orifice, a normally closed port arranged to be opened when the pressure in said chamber is reduced, a 90 pipe, means responsive to traffic conditions for at times connecting said chamber with said pipe, a reservoir, a manually operable valve for at times connecting said pipe with said reservoir, and means including said port 95 for at times connecting said reservoir with atmosphere.

4. Railway traffic controlling apparatus comprising a brake application valve having a chamber constantly supplied with fluid pressure through a restricted orifice, a normally closed port arranged to be opened when the pressure in said chamber is reduced, a pipe, means for connecting said pipe with atmosphere or with said chamber 100 according as traffic conditions are safe or dangerous, a reservoir connected with atmosphere when said port is open, and a manually operable valve for at times connecting said pipe with said reservoir.

5. The combination, in railway traffic controlling apparatus comprising an application valve having a pressure chamber constantly supplied with fluid pressure through a restricted orifice and a slide valve responsive to the pressure in said chamber; of a pilot valve arranged to be closed only when the engineman's brake valve is in the lap position, means controlled by said slide valve for at times connecting said chamber with said pilot valve, a pipe, means for connecting said pipe with atmosphere or with said chamber depending upon traffic conditions, a reservoir, means controlled by said slide valve for at times connecting said reservoir with atmosphere, and a manually operable valve for connecting said pipe with said reservoir or with said pilot valve.

6. The combination, in railway traffic controlling apparatus comprising an applica-

tion valve having a pressure chamber constantly supplied with fluid pressure through a restricted orifice and a slide valve responsive to the pressure in said chamber; of a 5 pilot valve arranged to be closed only when the engineman's brake valve is in the lap position, means controlled by said slide valve for at times connecting said chamber with said pilot valve, a pipe, means for connecting 10 said pipe with atmosphere or with said chamber depending upon traffic conditions, a reservoir, means controlled by said slide valve for at times connecting said reservoir with atmosphere, a manually operable valve 15 arranged to connect said pipe with said reservoir when such manually operable valve is in one position and to connect said pipe with said pilot valve when said manually operable valve is in the other position, and 20 a check valve interposed between said pilot valve and said manually operable valve.

7. The combination, in railway traffic controlling apparatus comprising a brake application valve, and means responsive to 25 traffic conditions for at times moving said valve from its normal to its reverse position; of a pilot valve controlled in accordance with the position of the engineman's 30 brake valve, a manually controlled suppressing valve, a manually operable release valve, and means effective when said brake application 35 valve is in the reverse position and controlled by said suppressing valve and by said pilot valve and by said release valve for restoring said brake application valve to its normal position.

8. The combination, in railway traffic controlling apparatus comprising an application valve having a pressure chamber constantly supplied with fluid pressure through a restricted orifice and a slide valve arranged to occupy a normal or a reverse position depending upon the pressure in said chamber; of a pilot valve controlled in accordance 40 with the position of the engineman's brake valve, means for at times reducing the pressure in said chamber whereby said slide valve moves to its reverse position, means effective when said slide valve is in its reverse 45 position for connecting said chamber with atmosphere, a port in said slide valve open when the valve is in its reverse position for connecting said chamber with said pilot valve, and a manually operable valve for at 50 times connecting said chamber with said pilot valve independently of the position of said slide valve.

9. Railway traffic controlling apparatus 60 comprising a brake application valve having a chamber constantly supplied with fluid pressure through a restricted orifice and a slide valve controlled in accordance with the pressure in said chamber, a pilot valve communicating with atmosphere and controlled in accordance with the position of the

engineman's brake valve, means controlled by traffic conditions for at times decreasing the pressure in said chamber, means controlled by said slide valve for connecting said chamber with said pilot valve and with atmosphere, and a manually operable valve for at times blanking such connection to atmosphere and for connecting said chamber directly with said pilot valve independently of said slide valve. 75

10. Railway traffic controlling apparatus comprising a brake application valve having a chamber constantly supplied with fluid pressure through a restricted orifice and a slide valve controlled in accordance with the pressure in said chamber, a pipe, a pilot valve controlled in accordance with the position of the engineman's brake valve for at times connecting said pipe with atmosphere, means controlled in accordance with traffic 80 conditions for at times decreasing the pressure in said chamber, means controlled by said slide valve for at times connecting said pipe with said chamber, and a manually operable valve for connecting said pipe with said chamber or with atmosphere depending upon the position of such manually operable valve. 90

11. Railway traffic controlling apparatus comprising a brake application valve having a chamber constantly supplied with fluid pressure through a restricted orifice and a slide valve controlled in accordance with the pressure in said chamber, a pilot valve closed only when the engineman's brake valve is in the lap position, pipe communicating with atmosphere through said pilot valve, means controlled in accordance with traffic conditions for at times decreasing the pressure in said chamber, means controlled by said slide valve for at times connecting said pipe with said chamber, and a manually operable valve for selectively connecting said pipe with said chamber or with atmosphere. 95

12. Railway traffic controlling apparatus comprising a chamber normally supplied with fluid pressure, automatic brake applying mechanism on a train controlled in accordance with the pressure in said chamber, a pilot valve closed only when the engineman's brake valve is in a predetermined position, a manually operable valve capable of assuming a normal or a reverse position, means responsive to traffic conditions for at times connecting said chamber with atmosphere through said manually operable valve in its normal position, and means effective when said manually operable valve is in its reverse position for connecting said chamber with atmosphere through said pilot valve. 110

13. Railway traffic controlling apparatus comprising a train carried brake application valve having a chamber constantly supplied with fluid pressure through a restricted orifice, a slide valve arranged to occupy a nor- 115 120 125 130

- mal or a reverse position depending upon the pressure in said chamber, automatic apparatus for applying the brakes when said slide valve is in its reverse position, a normally open manually operable valve, and means effective upon a change from less restrictive to more restrictive traffic conditions in advance to connect said chamber with atmosphere through said manually operable valve, said means being effective upon a change from more restrictive to less restrictive conditions to disconnect said chamber from atmosphere independently of said manually operable valve.
- 15 14. Railway traffic controlling apparatus comprising a brake application valve capable of assuming a normal or a reverse position, means responsive to traffic conditions for at times moving said brake application valve to its reverse position, a manually operable valve, means controlled by said brake application valve and effective when said manually operable valve is normal but not when said manually operable valve is reversed to maintain said brake application valve in its reverse position, and other means controlled by the engineman's brake valve and effective only when the manually operable valve is reversed for causing said brake application valve to occupy its reverse position.
15. Railway traffic controlling apparatus comprising a train carried brake application valve having a chamber constantly supplied with fluid pressure through a restricted orifice, a port in said valve normally closed but arranged to be opened when the pressure in said chamber is reduced below a predetermined value, automatic brake application mechanism controlled by said brake application valve, a manually operable release valve on the train accessible to the engineman only when the train is at rest and having a normal and a reverse position, means responsive to traffic conditions and effective when said release valve is in its normal position for reducing the pressure in said chamber below such predetermined value, and means including said port for subsequently connecting said chamber with atmosphere, said last mentioned means being ineffective when said release valve is in its reverse position.

In testimony whereof I affix my signature.
HERBERT A. WALLACE.
